UNITED STATES PATENT OFFICE.

WILLIAM LANYON AND JOSIAH LANYON, OF PITTSBURG, KANSAS.

LADLING DEVICE.

SPECIFICATION forming part of Letters Patent No. 644,712, dated March 6, 1900.

Original application filed May 25, 1898, Serial No. 681,718. Divided and this application filed September 28, 1898. Serial No. 692,129. (No model.)

To all whom it may concern:

Be it known that we, WILLIAM LANYON and JOSIAH LANYON, citizens of the United States, residing at Pittsburg, in the county of Crawford and State of Kansas, have invented certain new and useful Improvements in Ladling Devices; and we do hereby declare the following to be a full, clear, and exact description of the invention, such as will enable others skilled in the art to which it appertains to make and use the same.

Our invention relates to an invention in ladling devices for metallurgical purposes.

One object of our invention is to provide a ladling device particularly useful in connection with smelting-furnaces, where it is intended to remove molten material from retorts or the like and transport the same to another place.

20 A further object of our invention is to provide means for supporting the movable or traveling ladling mechanism in such manner that the workmen can approach much nearer to said mechanism while standing on the ground in front of the furnace plant for the purpose of tilting or raising and lowering the ladle to bring the latter in proper position before the retort-condensers.

Another object is to provide a drawing-shield for the protection of the workmen, which from the nature of its construction furnishes a means for the circulation of air or other cooling medium therethrough, as well as furnishing a structure of increased strength 35 for the direct support of the ladle and the means both for raising and lowering the same.

A still further object is to provide means for holding the ladle in position positively both when tilted in one direction beneath the 40 condensers and when tilted in the other direction to discharge the accumulated contents thereof taken from said condensers.

Our invention is especially useful in connection with a zinc-smelting plant, such as 45 has been shown and described in our application, Serial No. 681,718, filed May 25, 1898, of which this application is a division.

Our invention consists in the features, details of construction, and combination of

parts, which will first be described in connection with the accompanying drawings and then particularly pointed out in the claims.

In the drawings, Figure 1 is a front elevation of a device embodying our invention; Fig. 2, a transverse section of the same on the line 2 2, Fig. 1; Fig. 3, a similar section on the line 3 3, Fig. 1; Fig. 4, a horizontal section on the line 4 4, Fig. 1. Fig. 4^a is a detail view, partly in section, of the cam device for moving the ladle transversely; Figs. 5 and 6, detail end elevations showing the ladle in two different positions. Fig. 7 is a detail end elevation showing the ladle as it appears when discharging its load into a receiving-pot.

Referring to the drawings, it will be seen 65 that our invention comprises a drawing-shield which consists of a pair of hollow air-chests Q, having air-inlets q in their outer faces at the lower ends and openings at their top ends, as indicated at q', Fig. 2. These air-chests are each provided at their adjacent upper corners with hangers q², on which are mounted grooved sheaves q³, running on an upper rail p' and fixed on axles q⁴, to one of which is secured at the outer end a sprocket-wheel q⁵. The hangers are braced and the air-chests still further supported by brace-hangers q⁶, secured to the outer corners of the air-chests and to the hangers, as shown in Fig. 1. The lower ends of the air-chests 80 are connected rigidly by a transom-piece q⁷, while the upper ends are securely held together by a stringer q⁸. In the space thus formed between the air-chests is located a vertically-movable ladle R, having trunnions 85 mounted in a swing or swinging frame, in the present instance consisting of side rods r, connected at the top end by a transverse brace r' and provided at its extreme upper ends with holes, into which are hooked chains 90 r², whose other ends are connected to and arranged to be wound upon drums r³, fixed on an axle r⁴, mounted revolvably in journals r⁵, fixed to the hangers q². The axle r⁴ is extended at one end and carries a worm-wheel 95 r⁶, engaged by a worm r⁷, mounted in bearings r⁸, fixed to one of the air-chests. A sprocket-wheel r⁹ is fixed to the same axis as

the worm and is arranged to be rotated by a sprocket-chain r^{10} , passing over the sprocket-wheel r^9 and around a driving sprocket-wheel r^{11} , revolvably mounted on a stud r^{12} , fixed in 5 a cross-piece r^{13} , secured to one of the air-chests. The hub of the driving sprocket-wheel r^{11} is extended to form a sleeve r^{14} , to which are attached a hand-wheel r^{15} and a crank r^{16} .

10 On one of the side rods r is located a journal r^{17} , in which is mounted the axis r^{18} of a worm r^{19} , which engages a worm-wheel r^{20} , fixed on the corresponding trunnion of the ladle. The axis r^{18} of the worm is provided 15 with a hand-wheel r^{21} .

Each side rod r is provided intermediate its length with an opening, through which passes a stud r^{22} , these studs being provided with handles r^{23} and with cams r^{24} , which are arranged 20 to bear against the sides of flanges q^9 , secured to the inner adjacent edges of the air-chests.

Around the sprocket-wheel q^5 , secured to the axle q^4 of the roller q^3 , is placed a sprocket-chain q^{10} , which passes also around a sprocket-wheel q^{11} , provided with a long hub mounted on a stud q^{12} , fixed to a cross-piece q^{13} , fixed to one of the air-chests Q , the hub of the sprocket-wheel q^{11} being provided with a 30 crank q^{14} .

To the remote edges of the air-chests are hinged swinging wings Q' .

The operation of our device is as follows: When it is desired to draw off the molten metal, the drawing-shield is moved along the tracks p^1 and p^2 to a position where its ladle R will be in the same vertical plane as the condensers which are to be emptied, it being assumed that the ladle is in its lowest position. This movement of the drawing-shield is produced by rotating the crank q^{14} , which by means of the sprocket-wheels q^{11} and q^5 and the chain q^{10} rotates the roller q^3 , resting on the track P' . The wings Q' are swung 45 outward at an angle to the air-chests Q in order to protect the workmen against the heat which might reach them laterally from the retorts not covered by the drawing-shield. The air entering the air-chests Q through the 50 openings q and passing out through the open top ends at q' will keep the said air-chests cool, and thus protect the workmen. The handle r^{16} being rotated will lift the ladle R until its inner lip is close under the outer end 55 of the lowest condenser of the row. The molten metal is then scraped or dipped from the condenser into the ladle by means either of a scraper or of a small hand-ladle in the usual manner. Then the ladle is swung outward 60 away from the retorts by turning the cam-levers r^{23} , thus allowing the inner lip of the ladle R to clear the end of the condenser which has just been discharged. The handle r^{16} is again rotated in the desired direction to 65 wind up the chains r^2 and lift the ladle to a point beneath the next higher condenser to be discharged, whereupon the cam-levers or

handles r^{23} are again swung so as to allow the ladle R to move inward with its inner lip close under the outer end of said next highest condenser, which may be then tapped in the usual manner. The operations of drawing off the zinc, above described, may be repeated until the ladle is filled, whereupon the drawing-shield is run along its tracks until its ladle is opposite the place where it is to be discharged. The hand-wheel r^{21} is then rotated to turn the ladle on its trunnions and cause it to empty its load.

From the construction and arrangement shown and described it will be seen that we dispense with the use of a double track-rail in front of the furnace at the bottom, as well as with an independent carriage for the ladle mechanism and its support, and in this way the workmen can approach much closer in handling the ladle, and they can also perform their necessary duties while standing on the ground, which latter feature renders the work easier and gives greater freedom of action. It will also be seen that the ladle is held positively to the different positions to which it is brought and that in virtue of the air-chests of the shield being made of two walls each the said shield, in addition to its function as such, furnishes a much stronger support for the mechanism than if the chests thereof were only of a single wall each.

Having thus fully described our invention, what we claim as new, and desire to secure by Letters Patent, is—

1. In a furnace plant comprising a plurality of retorts the combination of a workman's protective shield, means for moving the same longitudinally before the ends of the retorts, a ladle movably supported upon the shield, means for moving the ladle upon its supports toward and away from the retorts, means for raising and lowering the ladle, and means for tilting the ladle outwardly and downwardly from the retorts to empty the same of its contents.

2. In a furnace plant comprising a plurality of retorts, the combination of a workman's protective shield, means for movably supporting the shield, a ladle movably supported on the shield, means for moving the ladle upon its supports toward and away from the retorts, means for raising and lowering the ladle, and means for tilting the ladle outwardly and downwardly from the retorts to empty the same of its contents.

3. In a furnace plant comprising a plurality of retorts the combination of a workman's protective shield, means for movably supporting the shield, a ladle movably supported on the shield, means supported directly upon the shield for moving the ladle upon its supports toward and away from the retorts, means for raising and lowering the ladle, and means for tilting the ladle outwardly and downwardly from the retorts to empty the same of its contents.

4. In a furnace plant comprising a plurality

of retorts the combination of a workman's protective shield, means for movably supporting the shield, a ladle, means supported directly upon the shield for swinging the ladle toward and away from the retorts, and means also supported directly upon the shield for tilting the ladle outwardly and downwardly from the retorts to empty the same of its contents.

5. In a furnace plant comprising a plurality of retorts, the combination of a workman's protective shield, means for movably supporting the shield, a ladle, means for raising and lowering the ladle, means supported directly upon the shield for moving the ladle toward and away from the retorts, and means also directly supported upon the shield for tilting the ladle outwardly and downwardly from the retorts to empty the same of its contents.

6. In a furnace plant comprising a plurality of retorts the combination of a workman's protective shield, means for movably supporting the same, a ladle movably supported on the shield, means supported directly upon the shield for raising and lowering the ladle, and for holding the same in such position positively, means supported directly upon the shield for moving the ladle toward and away from the retorts, and for holding the same in such position positively, and means also supported directly upon the shield for tilting the ladle outwardly and downwardly from the retorts, to empty the same of its contents, and also for holding the ladle in this position positively while such emptying is effected.

35 7. In a furnace plant comprising a plurality of retorts the combination of a suspended traveling protective shield for the workmen, means supported directly thereon for moving the same longitudinally before the retorts, a ladle movably supported thereon, means supported directly upon the shield for moving the ladle toward and away from the retorts, means directly supported upon the shield for raising and lowering the ladle, and means also directly supported upon said shield for tilting the ladle outwardly and downwardly from the retorts to empty the same of its contents.

8. In a furnace plant, comprising a plurality of retorts the combination of a protective shield constructed of a pair of connected air-chests movable in front of the retorts, and separated from each other by a space, a ladle movably supported between the chests, means supported directly upon the chests for moving the shield longitudinally before the retorts, means supported directly upon the shield for moving the ladle toward and away from the retorts, means directly supported upon the shield for raising and lowering the ladle and its supports, and means also di-

rectly supported upon said shield for tilting the ladle outwardly and downwardly.

9. In a furnace plant, the combination with a plurality of retorts, and a track adjacent to the front ends of the retorts, of a pair of connected air-chests mounted on said tracks and having their adjacent vertical edges separated from each other, said edges forming ways, ladle-supporting mechanism mounted in said ways, a ladle mounted in said ladle-supporting mechanism, and means carried by the air-chests for raising and lowering said ladle-supporting mechanism.

10. In a furnace plant, the combination, with a furnace a track adjacent to said furnace, and a pair of connected air-chests movable along said track and separated from each other, of a ladle-supporting device mounted directly upon and movable vertically between the adjacent edges of the air-chests and provided with bearings, a ladle provided with trunnions mounted in said bearings, and mechanism carried by the ladle-supporting device for rotating the ladle on its trunnions.

11. In a furnace plant, the combination with a plurality of retorts, a track adjacent to the retorts, and a shield movable along said track, of a ladle-supporting device carried by the shield, and means acting intermediate the ladle-supporting device and the shield, for swinging the ladle away from the front of the furnace.

12. In a furnace plant, the combination with a plurality of retorts, and a track adjacent to said retorts, of a pair of connected air-chests mounted on rollers movable on said track a flange secured to one of the air-chests, a ladle mounted between the air-chests, means for raising and lowering the ladle and a cam bearing upon the flange and arranged to move the ladle away from the front of the furnace.

13. In a furnace plant, the combination, with a plurality of retorts, and a track adjacent to said retorts, of a pair of connected air-chests mounted on rollers movable on said track, a flange secured to one of the air-chests, a ladle, a swinging frame supporting said ladle, mechanism carried by the air-chests for raising and lowering said ladle, and a cam attached to the swinging frame and arranged to bear on the flange.

In testimony whereof we affix our signatures in presence of two witnesses.
